BINOCULAR

Stanley J. Bailey, Snyder, N. Y., assignor to
Spencer Lens Company, Buffalo, N. Y., a corporation of New York

Application February 9, 1940, Serial No. 318,128

8 Claims. (Cl. 88—34)

This invention relates to binoculars and more particularly to improved means and method for connecting the parts thereof.

One of the objects of the invention is to provide improved means and method for connecting the parts of a binocular which will be more economical to manufacture and assemble.

Another object of the invention is to provide an improved eyepiece for binoculars and improved means and method for securing the said eyepiece to the other parts of the binoculars.

Another object is to provide an improved hinge means for binoculars which will prevent corrosion and provide a more durable construction and thereby lengthen considerably the period of use of the binoculars.

Another object is to provide improved binocular hinge means which will prevent the parts from loosening and separating from use and wherein the parts can be adjusted to vary the tension on the connection and also compensate for wear of the parts.

Another object is to provide such a device wherein the various members are so associated that they function as an integral part of the body of the binoculars.

With prior art constructions of binoculars there have been a number of difficulties with the hinge members. If the parts wore, there was no way of compensating for the wear and the entire binocular had to be discarded. Occasionally, dirt or water would work its way into the hinge members and corrosion would occur, ruining the binocular. Another difficulty was that the parts were difficult to assemble requiring considerable hand fitting of the parts and skilled help was required for this purpose making the cost of assembling a very considerable portion of the cost of the finished product.

In prior constructions there was also trouble caused by dust or water seeping into the casings through the joints between the eyepieces and casings. This dust and water would gather on the surfaces of the lens elements in the casings and corrosion and reduced vision through the lens elements were caused thereby.

It is the object of this invention to provide a construction wherein the parts may be very easily and economically assembled without the necessity of skilled help, and it is practically impossible for dirt or water to seep in the hinge joints or casings and corrosion is thereby prevented. Also the hinge means can easily and quickly be adjusted to compensate for any wear on the parts.

Referring to the drawings:

Fig. 1 is a plan view of a pair of binoculars showing the hinge member in section.

Fig. 2 is an end view of the binocular.

5 Fig. 3 is a sectional view taken on line 3—3 of Fig. 1 and looking in the direction of the arrows.

Fig. 4 is a sectional view taken on line 4—4 of Fig. 1 looking in the direction of the arrows;

Fig. 5 is a sectional view taken on line 5—5 of 10 Fig. 1;

Fig. 6 is a view similar to Fig. 1, but showing a modification of the invention;

Fig. 7 is an end view of the binoculars shown in Fig. 6;

15 Fig. 8 is a sectional view taken on line 8—8 of Fig. 6 looking in the direction of the arrows;

Fig. 9 is a sectional view taken on line 9—9 of Fig. 6 looking in the direction of the arrows; and

Fig. 10 is a sectional view taken on line 10—10 20 of Fig. 6 looking in the direction of the arrows.

Referring more particularly to the drawings wherein similar reference characters designate corresponding parts throughout the several views, the device embodying the invention comprises a pair of casings 1 and 2 which contain the prisms 3 and to which are secured the eyepieces 4.

The casings 1 and 2, each containing an optical system are pivotally secured together to allow the casings to be adjusted or spaced apart so that the eyepieces are spaced apart the necessary pupillary distance to meet the requirements of the particular user, and also this adjustment may be quickly and easily varied to meet the requirements of other users and yet the adjusting means are so constructed as to prevent loosening or corrosion of the parts as set forth above.

The casing 1 is preferably made or molded of metal and the ears or extensions 5 and 6 are formed integral therewith. These ears 5 and 6 are provided with cut back or grooved portions 7 and 8 respectively which portions contain the eccentric perforations 9 and 10.

The casing 2 is also preferably made or molded 45 of metal and the ears or extensions 11 and 12 and the tubular connecting portion 13 having the cylindrical bore 14 are formed integral therewith. The extensions 11 and 12 have grooved portions so formed as to interfit with the grooved portions 7 and 8 of the extensions 5 and 6 on the casing 1.

The outer faces or ends of the extensions 11 and 12 are formed with circular grooves 15 and 16 around the ends of the cylindrical bore 14 into which are adapted to be secured by friction or 55 the like tubular bushings or bearing members 17.

and 18 which are preferably formed of bronze and lubricated; that is, impregnated with graphite or other lubricant. These members 17 and 18 are pressed or forced into the circular grooves 15 and 16 and as stated above are retained therein by friction.

The said circumferential bearing members 17 and 18 are provided with the tapered inner faces 19 and 20.

The pivot post or member 21 is then inserted into the bore 14 of the tubular connecting portion through the openings in the member 11 and has a tapered shoulder portion 23 which engages and bears against the tapered bearing member 19.

The tubular member 22 is adapted to fit into the bore 14 from the opposite end and through the opening 10 in the member 6 and engage in telescoping relation with the end of the member 21. This member 22 also has a tapered shoulder or portion 24 adapted to engage the tapered face 20 of the bearing member 18.

These members 21 and 22 are preferably formed of nickel silver, bronze or some other composition having similar properties.

I have found that by making the pivot members of a bronze bearing lubricated or impregnated with graphite or other lubricant and having a tapered surface which engages a tapered edge of a bushing of nickel silver, bronze or the like the pivot connection between the parts will possess qualities overcoming the defects in prior art constructions.

The telescoping members 21 and 22 are formed with eccentric head portions 25 and 26 of substantially D cross section as shown in Fig. 3. This prevents rotation of the members 21 and 22 and secures all of the parts together as though they were formed integral with the casings 1 and 2.

On the heads 25 and 26 of the members 21 and 22 are secured the caps 27 and 28 by screws or the like 29 and 30 which screw into openings in the ends of said members 21 and 22 to retain the parts in adjusted position.

By adjusting the screw 30 the desired tension may be obtained on the bearing members. It will be obvious from the drawings that by tightening the screw 30, the telescoping member 25 will be drawn through the aligned openings in the members 5, 11, 13 and 6. In this way, any desired amount of tension or friction can be obtained between the tapered bearing faces 19 and 20 on the circumferential bearing members 17 and 18 and the respective tapered faces 23 and 24 on the members 21 and 22. Also, any dust or moisture is prevented from entering the hinge connection.

This construction is particularly adapted and constructed so as to be easily, economically and quickly assembled. It is only necessary to interfit the portions 7 and 8 with the portions 11 and 12 with the openings in each of these members in aligned relation with the bore 14 in the connecting portion 13. The member 21 is then inserted in place with its tapered shoulder engaging the tapered face 19 of the bearing member 17 and the member 22 inserted into the opening in the member 6 so as to be in telescoping engagement with the end of the member 21 and with its tapered shoulder engaging the adjacent tapered face 20 of the bearing member 18. The caps 27 and 28 are then secured in place by the screws 29 and 30 which are then tightened to provide the desired tension between the hinge 75

members. It will be apparent that any slight adjustment or difference in size of the parts will be readily compensated for by the tapered shoulders and bearing members.

5 In the construction shown in Figs. 6, 7, 8, 9, and 10, the casing 1 is formed with the extensions 5 and 6 and the casing 2 is formed with the extensions 11 and 12 and has the integral tubular connecting portion 13, having the cylindrical bore 14, similar to the construction shown in Fig. 1. In this construction the ends of the cylindrical bore 14 are also provided with the bronze bearing members 17 or 18 impregnated with graphite or other lubricant similar to 15 the construction shown in Fig. 1.

In this construction the eyepieces 33 and 34 are adapted to be adjusted simultaneously through the crosspiece 35 which is moved back and forth through movement of the thumb wheel 36 to focus the lenses.

20 The member 37 formed of nickel silver, bronze or the like has the tapered shoulder 38 adapted to bear against the bearing member 17 and its other end extending into the bore of the nickel silver telescoping member 22 which has the tapered shoulder portion 24 bearing against the bearing 18 and held in place by the cap 41 which has the screw 42 secured to the end of the member 37. The member 37 has its head 43 of substantially a D shape as is the opening in the end of the member 5. The eccentric or D-shaped member 22 fits in the similar shaped opening in the member 6. This prevents movement of the parts as previously described in connection with the construction shown in Fig. 1.

25 The member 44 has the threaded portion 45 adapted to engage the threads on the interior of the hollow portion 46 of the member 37 and when the thumb wheel 36 is turned these threaded portions cooperate to move the member 44 back and forth and thereby move the eyepieces to desired adjusted focus.

30 The member 44 also has a shoulder portion which supports the members 35 and 48 which are held thereon by the cap 49 which is held in position by the screw 50. The shoulder portion of the member 44 is secured to the member 48 by the screw or the like 51. This arrangement allows the pivoting of the casings to proper pupillary distance for the user as heretofore described.

35 With the form of construction shown and described it is possible first to prevent and minimize wear or play in the parts caused by repeated adjustment thereof and should such wear occur the parts can be easily and quickly adjusted to compensate therefor. Also it is possible to vary the tension on the contacting bearing surfaces of the pivoting parts to desired amount because of the tapered bearing connections. Also, it will be readily apparent that because of the tapered bearing surfaces the parts may be quickly and easily assembled without the trouble and expense incurred in assembling prior constructions.

40 In the construction of the eyepiece shown in section in the left hand side of Figure 1, and which is shown so adapted that the eyepiece may be adjusted by a thumb wheel type of binocular similar to that shown in Figure 6, although the connection between the eyepiece and casing is similar in both types, the connection between the eyepiece and casing is a sealed joint preventing the entrance of dust or moisture into the interior of the casing.

45 In this construction the eyepiece tube 52 and

the lens tube 58 are connected by a bellows 54 which may be of metal, rubber or other suitable material which will prevent the entrance of air and moisture.

The bellows 54 is secured at one end to the eyepiece tube 52 at 56. The other end of the bellows 54 is secured to the lens tube 58 at 59.

This prevents dust and moisture entering into the interior of 57.

With this construction the interior of the 10 casing may be filled with nitrogen or desiccated air to prevent fogging of the lenses in sudden temperature changes, and dust and water vapor will be prevented from entering the casing and, therefore, no corrosion can occur or damage to the 15 surfaces of the lenses in the casing thereby obviating disadvantages found in prior art constructions.

From the foregoing, it will be seen that I have provided simple, efficient and economical means 20 for accomplishing all of the objects of the invention and overcoming many of the disadvantages of prior art types of binoculars, and whereby the parts may be made and assembled more quickly and inexpensively than was possible with prior constructions.

Having described my invention, I claim:

1. In a binocular, a hinge connecting the telescopes of said binocular comprising a pair of outer and a pair of inner arms, the hinge arms of one of the single telescopes being outer ones and those of the other single telescope being inner ones, each of said arms having openings adapted to be aligned with the openings in the other of said arms, the inner arms having tapered bearing surfaces surrounding the said openings on their outer sides, a pair of telescoping pivot members adapted to extend into said aligned openings, one from each end thereof, and having tapered bearing faces adapted to 40 engage the tapered bearing faces on said arms, and means for locking said telescoping members in telescoping relation with each other with their tapered bearing faces in engagement with the tapered bearing faces on said arms to retain said telescopes in adjusted pivotal relation with each other.

2. In a binocular, a hinge connecting the telescopes of said binocular comprising a pair of outer and a pair of inner arms, the hinge arms of one of the single telescopes being outer ones and those of the other single telescope being inner ones, each of said arms having openings adapted to be aligned with the openings in the other of said arms, the inner arms having tapered bearing surfaces surrounding the said openings on their outer sides, a pair of nickel silver telescoping pivot members adapted to extend into said aligned openings, one from each end thereof, and having tapered bearing faces adapted to engage the tapered bearing faces on said arms, and means for locking said telescoping members in telescoping relation with each other with their tapered bearing faces in engagement with the tapered bearing faces on said arms to retain said telescopes in adjusted pivotal relation with each other.

3. In a binocular, a hinge connecting the telescopes of said binocular comprising a pair of outer and a pair of inner arms, the hinge arms of one of the single telescopes being outer ones and those of the other single telescope being inner ones, each of said arms having openings adapted to be aligned with the openings in the other of said arms, the inner arms having tapered bearing 75

surfaces surrounding the said openings on their outer sides, a pair of bronze telescoping pivot members adapted to extend into said aligned openings, one from each end thereof, and having tapered bearing faces adapted to engage the tapered bearing faces on said arms, and means for locking said telescoping members in telescoping relation with each other with their tapered bearing faces in engagement with the tapered bearing faces on said arms to retain said telescopes in adjusted relation with each other.

4. In a binocular, a hinge connecting the telescopes of said binocular comprising a pair of outer and a pair of inner arms, the hinge arms of one of the single telescopes being outer ones and those of the other single telescope being inner ones, each of said arms having openings adapted to be aligned with the openings in the other of said arms, the inner arms having lubricated tapered bearing surfaces surrounding the said openings on their outer sides, a pair of telescoping pivot members adapted to extend into said aligned openings, one from each end thereof, and having tapered bearing faces adapted to engage the tapered faces on said arms, and means for locking said telescoping members in telescoping relation with each other with their tapered bearing faces in engagement with the tapered bearing faces on said arms to retain said telescopes in adjusted pivotal relation with each other.

5. In a binocular, a hinge connecting the telescopes of said binocular comprising a pair of outer and a pair of inner arms, the hinge arms of one of the single telescopes being outer ones and those of the other single telescope being inner ones, each of said arms having openings adapted to be aligned with the openings in the other of said arms, the inner arms having lubricated tapered bearing surfaces surrounding the said openings on their outer sides, a pair of nickel silver telescoping pivot members adapted to extend into said aligned openings, one from each end thereof, and having tapered bearing faces adapted to engage the tapered bearing faces on said arms, and means for locking said telescoping members in telescoping relation with each other with their tapered bearing faces in engagement with the tapered bearing faces on said arms to retain said telescopes in adjusted pivotal relation with each other.

6. In a binocular, a hinge connecting the telescopes of said binocular comprising a pair of outer and a pair of inner arms, the hinge arms of one of the single telescopes being outer ones and those of the other single telescope being inner ones, each of said arms having openings adapted to be aligned with the openings in the other of said arms, the inner arms having lubricated tapered bearing surfaces surrounding the said openings on their outer sides, a pair of bronze telescoping pivot members adapted to extend into said aligned openings, one from each end thereof, and having tapered bearing faces adapted to engage the tapered bearing faces on said arms, and means for locking said telescoping members in telescoping relation with each other with their tapered bearing faces in engagement with the tapered bearing faces on said arms to retain said telescopes in adjusted pivotal relation with each other.

7. In a binocular, a hinge connecting the telescopes of said binocular comprising a pair of outer and a pair of inner arms, each of said arms having openings adapted to be aligned with the

openings in the other of said arms, the inner arms having tapered bearing surfaces surrounding the said openings on their outer sides, a pair of telescoping pivot members adapted to extend into said aligned openings, one from each end thereof, and having tapered bearing faces adapted to engage the tapered bearing faces on said arms, and means for locking said telescoping members in telescoping relation with each other with their tapered bearing faces in engagement with the tapered bearing faces on said arms to retain said telescopes in adjusted pivotal relation with each other.

8. In a binocular, a hinge connecting the telescopes of said binocular comprising a pair of outer and a pair of inner arms, each of said

arms having openings adapted to be aligned with the openings in the other of said arms, the inner arms having tapered bearing surfaces surrounding the said openings on one side of said arms, a pair of telescoping pivot members adapted to be extended into said aligned openings, one from each end thereof, and having tapered bearing faces adapted to engage the tapered bearing surfaces on said arms, and means for locking said telescoping members with their tapered bearing faces in engagement with the tapered bearing faces on said arms to retain said telescopes in adjusted pivotal relation with each other.

STANLEY J. BAILEY.
